Attorney

UNITED STATES PATENT OFFICE.

JOHN A. WHITTAKER, OF DETROIT, MICHIGAN.

DEVICE FOR LEVELING WOODEN FLOOR SLEEPERS.

Application filed November 7, 1923. Serial No. 673,347.

To all whom it may concern:

Be it known that I, JOHN A. WHITTAKER, citizen of the United States, residing at Detroit, county of Wayne, State of Michigan, have invented a certain new and useful Improvement in Devices for Leveling Wooden Floor Sleepers, and declare the following to be a full, clear, and exact description of the same, such as will enable others skilled in the art to which it pertains to make and use the same, reference being had to the accompanying drawings, which form a part of this specification.

My invention relates to a device for leveling wooden floor sleepers shown in the accompanying drawings and more particularly described in the following specification and claims.

In laying wooden flooring upon a concrete base it is essential that the floor sleepers to which the wood flooring is nailed should be properly leveled in order that the flooring nailed to the sleepers may be on a horizontal plane.

Heretofore it has been customary to insert shims or wedges beneath the sleepers in order that they may be properly leveled upon the concrete bed or slab before the concrete filling is poured between the sleepers to the level of the top of the latter. It has therefore required considerable time and labor to properly "lay-up" the sleepers upon an even plane before the concrete filling can be poured between the latter, and the time thus expended represents a large proportion of the cost of building a floor of this character.

The purpose of this invention therefore is to provide means whereby the sleepers may be quickly and easily leveled upon the concrete base or foundation which means is adapted to be readily adjusted to provide an even surface to which the floor may be nailed.

A further object of this invention is to provide a device which is adapted for a relatively wide range of adjustment by the mere reversal of the supporting shoe with reference to the sleeper and by reinserting the supporting screws in the shoe.

A further object of this invention is to provide a device which is comparatively in-

expensive to manufacture and at the same time sufficiently strong for the purposes designed.

With the foregoing and other objects in view which will appear as the description proceeds the invention further resides in the combination and arrangement of parts and in the details of construction hereinafter described and claimed it being understood that changes may be made in the precise embodiment of the invention herein described without departing from the spirit of the same.

In the drawings accompanying this specification:

Figure 1 is a side elevation of the device as it would appear when supporting a sleeper, shown in cross-section, upon a rough floor level or base.

Figure 2 is an end elevation of the same and indicating a fragmentary portion of a sleeper supported in the device.

Figure 3 is a view similar to Figure 1 with the supporting screws reinserted in the opposite side of the shoe that the latter may be adapted for a relatively wider range of adjustment for supporting the sleeper mounted therein.

Figure 4 is an end elevation of the device shown in Figure 3 with a fragment of a sleeper resting thereon.

Figure 5 is a vertical fragmentary cross-sectional view through a floor sleeper, the concrete slab forming the rough floor level and also the concrete filling, poured between the sleepers.

Referring now to the letters of reference placed upon the drawings:

A denotes a rough floor level or slab of concrete.

B represents a wooden sleeper and C, a supporting shoe having a relatively deep channel portion C¹ to receive the wood sleeper B to which the flooring is nailed.

E, E, indicate screws projecting through laterally extended flanges C^a, by adjusting which the sleeper may be raised or lowered as required to insure a level surface to support the flooring.

C², C² designates flanges projecting downwardly from the bottom of the shoe between which the sleeper may be mounted,—as shown in Figures 3 and 4,—when it is de-

sired to provide for a greater adjustment of the sleeper than would be possible when mounted upon the screws as shown in Figure 1.

5 F, denotes a concrete filling poured between the sleepers level with the top of the latter,—see Figure 5.

D represents a wood flooring nailed to the sleepers.

10 Having now indicated the several parts by reference letters the construction and operation of the device will be readily understood.

15 A rough floor level of concrete having been properly prepared, the sleepers B to which the wooden flooring D is afterwards attached,—are supported in a plurality of the yoke-shaped shoes C, spaced apart throughout the length of the sleepers,—the 20 workman then proceeds to adjust the sleepers by means of the screws or bolts E so as to bring the top of the wooden sleepers to a uniform altitude throughout the surface of the floor. The sleepers having thus been 25 properly leveled, the concrete filling F is poured between the sleepers until it reaches a level on a plane with the top of the latter. The sleepers supporting devices are thus embedded in the concrete together with the 30 sleepers. The wooden floor is then nailed

to the top of the sleepers in the usual manner.

Having thus described my invention what I claim is:

1. A device of the character described comprising a unitary element of channel-like form in cross-section adapted to receive and support a floor strip, said element having flanges integral therewith extending outwardly from its side walls to provide a relatively broad support for the floor strip, and a plurality of adjustable screws projecting through holes tapped in said flanges for regulating the altitude of the device with reference to a floor level. 35

40 2. In a device of the character described, a U-shaped shoe for supporting a floor sleeper having laterally projecting flanges tapped to receive supporting screws or bolts, adjustable screws or bolts mounted in said flanges, 45 said shoe also provided with ribs extending downwardly from the base of the shoe and spaced apart to receive a sleeper when reversed upon the supporting screws or bolts. 50

55 In testimony whereof, I sign this specification in the presence of two witnesses.

JOHN A. WHITTAKER.

Witnesses:

S. E. THOMAS,
MAURICE WOLF.
